EUGENE F. CLARK, OF LEAKSVILLE, NORTH CAROLINA, ASSIGNOR TO MARSHALL FIELD MILLS CORPORATION, OF PHILADELPHIA, PENNSYLVANIA, A CORPORATION OF PENNSYLVANIA.

TUBE FRAME FOR TUFTED-PILE-FABRIC LOOMS.

Application filed July 9, 1925. Serial No. 42,393.

This invention relates to improvements in tuft yarn frames of carriers, commonly called "tube frames" for looms for weaving tufted pile fabric.

5 These frames each carry a spool or bobbin on which are wound a number of tuft yarn strands, and each frame is provided with a row of holding, spacing and guiding devices corresponding in number with the strands 10 of thread for receiving, retaining and delivering the strands to the grippers of the loom which, at certain intervals, during the weaving operation, draw predetermined lengths of the strands through and from the 15 guiding devices, such lengths being then cut from the strands to form the pile tufts.

The present invention aims to improve the 20 yarn guiding devices by providing a novel, simple and efficient construction thereof whereby the yarn strands are guided and held in proper spaced relation to be grasped by the grippers of the loom, and whereby the 25 yarn strands may be quickly and easily inserted into the guiding devices both when the yarn frame is on the loom, as occasion 30 may require, and also during the preparation of the yarn frame for the loom when the 35 yarn strands are wound upon the spools or bobbins and the free ends thereof inserted 40 into the guiding devices. The invention thus obviates the use of temporary guides or holding devices and special threading machines and permits the individual strands to be inserted into the guiding devices as they 45 are successively selected in accordance with a particular pattern, during the preparation 50 of the yarn frame for the loom.

The invention consists of the elements and the combinations of them hereinafter 55 described and claimed.

In the accompanying drawings, illustrating the invention,

Figure 1 is a front view of a tuft yarn frame partly broken away and provided 60 with tuft yarn holding and guiding devices embodying my invention.

Figure 2 is a transverse section thereof, on line 2-2 of Fig. 1.

Figure 3 is a section through the yarn 65 holding and guiding devices, on line 3-3 of Fig. 2.

Referring to the drawings, 4 designates

an elongated bar, forming the main body of the frame, and 5 brackets secured to and extending from the respective ends of the bar 4. The brackets 5 are of usual construction 55 and they provide bearings for the trunnions 6 of the spool or bobbin 7 which extends parallel to the bar 4 and which carries the tuft yarn strands 8 in the usual manner. 60

The frame bar 4 is provided with a strip of thin angle metal 9, such as tin, which is fitted against the front and bottom surfaces of the bar and which extends longitudinally of and is secured to the bar by means of 65 screws or nails 10.

The strip of angle metal 9 carries a row of spaced walls 11 which are soldered or otherwise suitably secured thereto and which project forwardly from the bar 4 and also 70 downwardly therefrom and back beneath the same, as clearly shown in the drawings. These walls 11 form yarn strand passages 12 between them for the yarn strands 8 which are drawn from the spool 7 down through 75 the passages.

The spaces between the upper end portions of the walls 11 form entrance openings for the passages 12, the spaces between the lower end portions of the walls 11 form exit openings for the passages 12, and the spaces between the forward edge portions of the walls 11 form front openings for the passages 12 which connect the entrance and exit openings thereof and through which the yarn strands 8 may be threaded into the passages from the front thereof, thus avoiding the necessity of threading the strands downwardly and longitudinally through the passages, as is necessary in prior constructions wherein the 80 passages are closed at the front thereof or are substantially tubular in form. In other words, the passages 12 are closed only at the back and sides, leaving the fronts thereof 85 entirely open for the easy threading of the 90 yarn strands into the same by moving the strands laterally as distinguished from longitudinally, as heretofore, into the passages.

Embracing the upper end portions of the walls 12 are the central portions of flat 100 springs 13, the end portions of which extend downwardly into the passages 12 and form a pair of flat spring arms 14 and 15 in each passage. The upper end portion of each

spring arm 14 and 15 is indented into an opening in the adjacent wall 11 to hold the arm in place within its passage 12. The spring arms 14 and 15 of each pair converge 5 downwardly from the entrance opening of its passage 12, and the lower or free end portions of the arms meet and lie flat against each other centrally of the ends and sides of their passage 12.

- 10 The spring arm 14 of each pair is indented at the surface thereof which is in contact with its companion spring arm 15, forming an opening, cavity or indentation 16 therein and forming a projection 17 at the opposite 15 surface thereof; and the said companion spring arm 15 of each pair is indented to form a projection 18 which extends into the indentation or opening 17 in the adjacent arm 14.
- 20 The free end portions of each pair of spring arms 14 and 15 which are normally in contact with each other may be separated or moved apart within its passage 12 to receive a yarn strand between them, and, 25 to permit a relatively wide range of opening between the arms of each pair within the narrow limits of the passage containing them to accommodate the yarn strands 8. I provide each wall 11 with a hole or opening 30 19 to receive the projection 17 of the adjacent spring arm 14 when it is separated from its companion arm 15.

The yarn strands 8 are drawn by the yarn grippers of the loom down through the 35 passages 12 between the pairs of spring arms 14 and 15 therein and between the projections 18 on the arms 15, which are located in the forward portions of the passages 12, and ribs 20 which are located in the rearward 40 portions of the passages 12 and which are formed on the metal strip 9 and extend longitudinally thereof throughout the length of the row of walls 11.

The ribs 20 serve to provide small area 45 contact surfaces between the rear walls of the passages 12 and the yarn strands 8 passing therethrough; and the projections 18 on the arms 15 serve as barriers to prevent the yarn strands 8 from accidentally leaving the 50 passages 12 through the front openings thereof.

The springs arms 14 and 15 of each pair terminate above or in spaced relation to the bottom of the walls 11 or the exit openings 55 of the passages 12 so that the grippers of the loom which draw the yarn strands 8 down through the passages may enter the lower end portions or exit openings thereof and grasp the free end portions of the 60 strands therein, and so that the walls 11 may prevent lateral displacement of the free end portions of the strands and retain them in alignment with the grippers to be grasped thereby.

65 The lower end portions of the walls 11

are widened, as illustrated, to contract the exit openings of the passages 12 so that they shall be narrower than the portions of the passages containing the spring arms 14 and 15, thus providing exit openings of sufficient 70 narrowness to retain the strands 8 in proper position to be grasped by the loom grippers, and providing the required room within the passages to accommodate the spring arms.

The lower end portions of each pair of 75 spring arms 14 and 15 are flared or extended outwardly, which, with the converging upper portions of the arms of each pair, permits the yarn strands to be easily passed between the arms of each pair when the 80 strands are threaded into the passages 12 through the front openings thereof; and, when the strands 8 are thus threaded into the passages and between the spring arms 14 and 15, the smooth inclined sides of the 85 projections 18 permit the pressure of the yarn against the same, during the threading operation, to separate the spring arms 14 and 15 sufficiently to move the yarn back into position back of the projections 18, after 90 which the spring arms 14 and 15 spring back against the strands 8 and hold them in place by the pressure exerted against them.

When the device is used in a loom, the 95 yarn carrier is periodically presented to the yarn grippers which, at each presentation, grasp the free end portions of the yarn strands 8 and draw the strands down through the passage 12 and between the spring arms 14 and 15 until lengths of the 100 strands corresponding to the lengths of the tufts to be inserted into the pile fabric have been drawn below the passages 12 or walls 11, whereupon the said lengths are cut from the strands beneath and close to the bottom 105 of the walls 11. Each time the yarn strands are thus drawn down through the passages 12, the spring arms exert sufficient friction upon the strands for the production of the desired tension of the strands, and, thereafter, the spring arms hold the free end portions of the strands in place for a succeeding drawing and cutting operation.

I claim as my invention:—

1. In a tuft yarn frame a body bar, a row 115 of spaced walls projecting therefrom and forming yarn strand passages between them, each passage having an entrance opening and an exit opening connected by a front opening through which a yarn strand may 120 be threaded, and a yielding barrier in each passage permitting a yarn strand to be threaded into the same through its front opening and preventing a yarn strand from accidentally leaving the passage through its 125 front opening.

2. In a tuft yarn frame a body bar, a row 130 of spaced walls projecting therefrom and forming yarn strand passages between them, each passage having an entrance opening

and an exit opening connected by a front opening through which a yarn strand may be threaded, and springs within said passages and adapted to frictionally engage 5 yarn strands passing therethrough.

3. In a tuft yarn frame a body bar, a row of spaced walls projecting therefrom and forming yarn strand passages between them, each passage having an entrance opening 10 and an exit opening connected by a front opening through which a yarn strand may be threaded, and springs embracing said walls at the inlet openings of said passages and extending into said passages and 15 adapted to frictionally engage yarn strands passing therethrough.

4. In a tuft yarn frame a body bar, a row of spaced walls projecting therefrom and forming yarn strand passages between them, 20 each passage having an entrance opening and an exit opening connected by a front opening through which a yarn strand may be threaded, and springs embracing said walls at the inlet openings of said passages 25 and having free end portions extending into said passages and terminating in spaced relation to the outlet openings thereof and adapted to frictionally engage yarn strands passing through the passages.

5. In a tuft yarn frame a body bar, a row of spaced walls projecting therefrom and forming yarn strand passages between them, each passage having an entrance opening and an exit opening connected by a front 30 opening through which a yarn strand may be threaded, and springs within said passages and adapted to frictionally engage 35 yarn strands passing therethrough, said springs having laterally extending portions forming barriers permitting yarn strands to be threaded into said passages through the front openings thereof and preventing yarn strands from accidentally leaving said 40 passages through the front openings thereof.

6. In a tuft yarn frame a body bar, a row of spaced walls projecting therefrom and forming yarn strand passages between them, each passage having an entrance opening and an exit opening connected by a front 45 opening through which a yarn strand may be threaded, and springs embracing said walls at the inlet openings of said passages and extending into said passages and adapted to frictionally engage yarn strands passing 50 therethrough, said springs having laterally extending portions forming barriers permitting yarn strands to be threaded into said passages through the front openings thereof and preventing yarn strands from 55 accidentally leaving said passages through the front openings thereof.

7. In a tuft yarn frame a body bar, a row of spaced walls projecting therefrom and forming yarn strand passages between them, each passage having an entrance opening 60

and an exit opening connected by a front opening through which a yarn strand may be threaded, and springs embracing said walls at the inlet openings of said passages and having free end portions extending into 70 said passages and terminating in spaced relation to the outlet openings thereof and adapted to frictionally engage yarn strands passing through the passages, said springs having laterally extending portions forming 75 barriers permitting yarn strands to be threaded into said passages through the front openings thereof and preventing yarn strands from accidentally leaving said 80 passages through the front openings thereof.

8. In a tuft yarn frame a body bar, a row of spaced walls projecting therefrom and forming yarn strand passages between them, each passage having an entrance opening and an exit opening connected by a front 85 opening through which a yarn strand may be threaded, and a pair of flat spring arms within each of said passages, the arms of each pair being adapted to receive a yarn strand between them and to frictionally engage the same.

9. In a tuft yarn frame a body bar, a row of spaced walls projecting therefrom and forming yarn strand passages between them, each passage having an entrance opening 95 and an exit opening connected by a front opening through which a yarn strand may be threaded, and a pair of flat spring arms within each of said passages, the arms of each pair being adapted to receive a yarn 100 strand between them and to frictionally engage the same, one arm of each pair being indented at one surface forming a projection at its opposite surface constituting a barrier permitting a yarn strand to be 105 threaded into its yarn strand passage through its front opening and preventing a yarn strand from accidentally leaving the passage through its front opening.

10. In a tuft yarn frame a body bar, a row of spaced walls projecting therefrom and forming yarn strand passages between them, each passage having an entrance opening and an exit opening connected by a front opening through which a yarn strand may 110 be threaded, and a pair of flat spring arms within each of said passages, the arms of each pair being adapted to receive a yarn strand between them and to frictionally engage the same, one arm of each pair being 115 indented at one surface forming a projection at its opposite surface constituting a barrier permitting a yarn strand to be threaded into its yarn strand passage through its front opening and preventing a 120 yarn strand from accidentally leaving the passage through its front opening, and the other arm of each pair having an opening 125 therein to receive the projection of its companion arm.

11. In a tuft yarn frame a body bar, a row of spaced walls projecting therefrom and forming yarn strand passages between them, each passage having an entrance opening and an exit opening connected by a front opening through which a yarn strand may be threaded, and a pair of flat spring arms within each of said passages, the arms of each pair being adapted to receive a yarn strand between them and to frictionally engage the same, one arm of each pair being indented at one surface forming a projection at its opposite surface constituting a barrier permitting a yarn strand to be threaded into its yarn strand passage through its front opening and preventing a yarn strand from accidentally leaving the passage through its front opening, and the other arm of each pair having an indentation therein to receive the projection of its companion arm.
12. In a tuft yarn frame a body bar, a row of spaced walls projecting therefrom and forming yarn strand passages between them, each passage having an entrance opening and an exit opening connected by a front opening through which a yarn strand may be threaded, and a pair of flat spring arms within each of said passages, the arms of each pair being attached to the walls of its yarn strand passage at the inlet opening thereof and having free end portions extending toward the exit opening of the passage and adapted to receive and frictionally engage a yarn strand passing therethrough, and the exit openings of said passages being narrower than the portions thereof containing said pairs of arms.
13. In a tuft yarn frame a body bar, a row of spaced walls projecting therefrom and forming yarn strand passages between them, each passage having an entrance opening and an exit opening connected by a front opening through which a yarn strand may be threaded, and flat springs embracing said walls at the inlet openings of said passages and terminating in a pair of arms within each passage extending toward the exit opening thereof and adapted to receive and frictionally engage a yarn strand passing therethrough, the exit openings of said passages being narrower than the portions thereof containing said pairs of arms.
14. A tuft yarn frame having a series of passages to receive yarn and provided with a series of rigid walls forming entrances for grippers spaced uniformly with said yarn passages, each yarn passage being provided with a broadside threading entrance whereby said passages can be threaded by hand.
15. A tuft yarn frame having a multiplicity of broadside hand threading passages to receive yarn, each passage being formed and constructed at one end thereof with an entrance for a gripper, and provided with means for imparting friction to the yarn intermediate the said gripper entrance and the source of yarn supply.

In testimony whereof I affix my signature hereto.

EUGENE F. CLARK.
